WELL DRILLER CLEANOUT PUMP
ASSEMBLY

Arnold S. Soberg, Elmhurst, and Ahlmann Christensen, Wilmette, Ill., assignors to Soehris Development Company, Chicago, Ill., a corporation of Illinois

Application November 30, 1951, Serial No. 259,124

15 Claims. (Cl. 103—219)

1

This invention is directed to new and useful improvements in Well Drillers Cleanout Pump Assembly wherein a pumping mechanism is positioned and removably secured in a well casing at the desired depth and the pump operated to move water from the casing.

The primary object of this invention is to provide a portable, sturdy, inexpensive pump mechanism with means whereby it can be lowered into a well casing and secured and sealed to the casing so that the first dirty liquid may be pumped to clean out the well before the more expensive permanent pumping means is installed.

Another object of this invention is to provide in such a mechanism a securing and sealing means adapted to operate simultaneously to either seal and secure the pump in a casing or unseal and release it by control above the ground in which the well casing is sunk.

Still another object of this invention is to provide in such an assembly a sucker rod which not only operates the pump piston but is used as a means by which the assembly is suspended when lowered into the casing and as control lever for effecting the securing and sealing action and release.

A further object of this invention is to provide a pump assembly which is adapted to be lowered into a well casing by a conventional well drillers rig, secured in pumping position at any desired depth and operated by the oscillating movement of the well drillers rig cable to pump liquid from the well.

And another object of this invention is to provide in such an assembly a control sleeve riding on the pump piston which will control the means for sealing the pump against the side of the casing.

Other objects and advantages will be apparent from the following detailed specifications:

In the drawings Fig. 1 is a schematic view partly in perspective and partly in enlarged section of a pump assembly embodying this invention secured in the lower part of a well casing and operable by the conventional well drillers rig.

Fig. 2 is an enlarged sectional view of the pump assembly shown in the lower part of Fig. 1 in suspended position before being secured and sealed within the casing.

Fig. 3 is a view similar to Fig. 2 but showing the pump assembly in secured and sealed position.

Fig. 4 is an alternate form of securing and sealing means.

2

In detail, 1 is a well casing and 2 indicates the conventional well drillers rig whereby the cable 3 may be oscillated up and down and lowered or raised as desired. The pump cylinder 4 has the usual irreversible inlet valve 5 at its bottom and the upper end is threaded internally as at 6. The usual pump piston 7 is provided with the usual irreversible inlet valve 8 and is secured to the lower end of the shaft 9 the upper end of which is provided with threads 10 to receive the cable socket 11 secured to the end of cable 3. A sleeve 12 fits loosely around shaft 9 and rests upon the upper surface of piston 7.

Threaded to the upper threads 6 of cylinder 4 is a support 13 on which a hollow sealing cup 14 is tiltably supported. Springs 15 normally hold cup 14 in horizontal or sealing position. A hollow slide block 16 is positioned around shaft 9 above cup 14 and a hollow wedge member 17 is positioned above it with shaft 9 extending therethrough. A pair of spaced arms 18 extend upwardly from block 16 at either side of rod 9 and hollow wedge member 17 is pivotally secured thereto at 22. These arms 18 also act as guides for slide block 16.

A connecting link 19 is pivotally joined to slide block 16 and wedge member 17. One edge of wedge 17 has teeth 20 and the opposite edge is rounded smooth as shown at 21. The distances between the pivot point 22 and lower left and upper right corners are greater than the corresponding distances to the other corners.

A spring 23 surrounds shaft 9 between the lower end of block 16 and an upper stop 24. A chain 25 connects the slide block 16 with one side of sealing cup 14.

In operation, cylinder 4 and attached assembly is secured to cable 3 by means of cable socket 11 and threads 10. The weight of the assembly will be carried by piston 7 through sleeve 12. The upper end of sleeve 12 will bear against lower surface of slide block 16 and will thus raise slide block 16 to position shown in Fig. 2. This in turn, through link 19, will cause wedge 17 to pivot and, through chain 25, will cause sealing cup 14 to tilt to the position shown in Fig. 2. In this position the whole assembly may be lowered into casing 1 to about the desired depth. At this point the assembly is allowed to drop a short distance. This dropping will momentarily relieve piston 7 from supporting the assembly and will move sleeve 12 out of contact with block 16.

The weight of slide block 16 and the action of springs 23 and 15 will rapidly move wedge 17 and cup 14 to securing and sealing positions re-

spectively. The wedge 17 will then grip casing 1 and the assembly becomes supported by wedge 17 and cup 14 effects a seal across the casing. As the piston 7 no longer supports the assembly it fails to position shown in Fig. 3 with sleeve 12 spaced below block 16. In this position piston 7 may be oscillated by cable 3 to pump liquid through valve 5 into cylinder 4 on the upstroke and through valve 3 above piston 7 on the downstroke. As this action continues liquid is moved up and out of casing 1.

To release the assembly for removal from the casing, the cable 3 is moved upward beyond the upper end of the normal pumping stroke so that sleeve 12 again contacts block 16. At this point a jerk of the cable will move block 16 upwardly to return wedge 17 and seal 14 to their respective positions shown in Fig. 2. The whole assembly may then be lifted out of the casing.

An alternate form of securing and sealing means is shown in Fig. 4. In this form, the wedge is formed of an anchored portion 26 held by a support 27 extending upwardly from the top of cylinder 28. Parallel links 29 extend on both sides of shaft 9 and are pivoted to portion 26 and are also pivotally connected to toothed portion 30. An adjustable stop screw 31 limits the downward movement of arms 29.

The sealing cup 32 fits on cylinder 28 but may be tipped out of sealing position by trigger 33 which extends downwardly and around shaft 9. A sleeve 34 fits around the shaft 9 and rides on the piston in the same manner as sleeve 12 in Figs. 2 and 3. A spring 35 tends to hold cup 32 in sealing position.

In operation the pump assembly is secured to the cable as above described and lowered into casing 1. The sleeve 34 will bear against the lower part of trigger 33 to move it upwardly to tilt sealing cup 32 out of horizontal sealing position. The weight of part 30 of the wedge assembly will hold it out of securing position. At the desired point in the liquid to be pumped the assembly is allowed to drop a short distance. This will cause the wedge portion 30 to swing to securing position and will release trigger 33 to permit spring 35 to move sealing cup 32 to sealing position. The assembly is released by moving the shaft 9 upwardly to cause sleeve 34 to actuate trigger 33 to tilt cup 32 which will spill the liquid above the seal. Then a pull upward will release the wedge assembly 26, 29 and 30.

It should be understood that the assembly may be lowered in the liquid without the securing means being actuated. However, when the assembly is dropped while in the liquid the resistance of the liquid will cause the arms 29 to swing toward horizontal to cause parts 26 and 30 to effectively grasp the inner sides of the casing 1.

Adjusting screw 31 permits the distance between portions 26 and 30 to be varied to accommodate slight variances in the inner diameters of well casings.

We claim:

1. In a well driller's cleanout pump assembly comprising a cylinder, piston and shaft, a means for securing and sealing the same within a well casing at a point remote from the ground level comprising a pivoted wedge and a tilttable sealing cup operably joined together and secured to the cylinder, a trigger actuated by the pump piston shaft when lifted upwardly above its normal upper stroke to tilt the sealing cup and pivot the wedge out of operative positions and means for returning the wedge to securing position and

the cup to sealing position when the piston is in normal pumping positions.

2. A device in accordance with claim 1 in which the piston shaft extends upwardly through the assembly and is provided with securing means at its upper end for fastening to a cable whereby the assembly may be lowered in the casing, secured, pumped and removed therefrom.

3. A well driller's cleanout pump assembly comprising a pump cylinder, a piston therein, a piston shaft secured to the piston, a sealing cup tiltably positioned at the top of the cylinder, a securing wedge rotatably positioned thereabove, a slide block therebetween, said piston shaft extending therethrough and above the wedge, means operably connecting the slide block with the wedge and the cup, an abutment on the piston shaft and positioned to contact the block when the piston is moved above its normal upper stroke position to rotate the wedge out of holding position and the cup out of sealing position, means urging their return from said positions and a fastening means at the upper end of the shaft for securing it to a cable whereby the assembly may be lowered into a well casing, secured and sealed therein and the piston moved up and down to pump liquid.

4. In a pump assembly comprising the usual pump cylinder, piston and shaft adapted to be lowered into a well casing by cable, be removably secured therein and operated by the cable to pump liquid from the casing, the invention comprising a tilttable sealing cup mounted on the cylinder, a tilttable wedge supported from the cylinder, the piston shaft extending above the assembly, securing means at the upper end of the shaft, means carried by the shaft for causing the cup and wedge to move out of operative positions when the shaft supports the assembly by its upper end and means urging the cup and wedge into operative positions when the weight of the assembly is removed from the shaft.

5. In an assembly according to claim 4, a slide block positioned between the wedge and cup, a link pivotally connecting the wedge and the block and a chain connecting the block and the cup, said means carried by the shaft adapted to move the block when the assembly is supported by the shaft to move the wedge and cup out of operative positions.

6. A well driller's cleanout pump assembly comprising a drilling rig, a cable suspended therefrom, a well casing sunk in the ground, a liquid pump, a tilttable seal mounted on the pump, a movable wedge mounted thereabove, an extension of the pumping shaft extending through the seal and wedge and secured to the cable, means carried by the shaft for moving the seal and wedge into inoperative position when the pump is suspended from the cable, means which will move the seal and wedge into operative positions when the weight of the pump is removed from the cable to secure the pump to the casing and effect a seal across the casing between it and the pump and means for moving the cable up and down to effect a pumping action of the piston within the pump.

7. In a well driller's cleanout pump assembly comprising a pump and means for removably securing and sealing the same within a well casing at a point remote from ground level, the invention comprising a tilttable seal mounted on the pump, resilient means normally holding it in sealing position, a trigger for moving it out of sealing position, an extension of the pump shaft passing through the seal, means for sus-

pending the assembly from the upper end of said shaft extension, a shoulder carried by the pump shaft for actuating said trigger when the assembly is suspended by the shaft, and a pivotable wedge carried by the assembly in non-securing position when the assembly is supported by the shaft but movable to securing position when the seal is moved to sealing position, both seal and wedge releasable when the shaft is moved upwardly above its normal pumping positions.

8. A device according to claim 7 in which a sleeve carried by the pump piston is the shoulder for causing the seal to be tilted out of sealing position.

9. A device according to claim 7 in which the securing wedge is held by gravity out of securing position but may be moved to gripping position when the device is suspended in liquid by the pressure thereof when the assembly is rapidly passed therethrough.

10. A device according to claim 7 in which the wedge comprises an anchored side, a movable side and pivoted arms connecting them.

11. A device according to claim 7, in which the wedge comprises an anchored side, a movable side, arms pivotally connecting them and an adjusting screw supporting a movable part of the wedge assembly to vary and limit the distance between the anchored and movable side portions.

12. A well drillers cleanout pump assembly for use in a well casing comprising a cylinder, an inlet valve at the bottom thereof, a piston therein, an inlet valve in the piston, a shaft connected to the piston and extending above the cylinder to form a supporting shaft, a connecting head at the upper end of the shaft, a tiltable sealing cup mounted on the cylinder for creating a seal across the well casing, means urging the cup into sealing position, means carried by the shaft for causing the cup to be tilted out of sealing position when the shaft

is above its normal upper pumping position and supporting the assembly by its connecting head, a pivoted wedge carried by the cylinder above the sealing cup and movable by manipulation of the supporting shaft into gripping engagement with the casing to support the assembly as the cup moves into sealing position, said seal and wedge movable out of sealing and securing positions respectively by an upward pull on the shaft when above its normal pumping positions.

13. A device according to claim 12 in which the wedge is weighted to normally assume non-securing position but movable to securing position by liquid pressure when the assembly is lowered rapidly through liquid.

14. A device according to claim 12 in which the wedge is mechanically linked with the seal to move out of securing position when the seal is tilted and spring means urging its return to securing position.

15. A well drillers cleanout pump assembly for use in a well casing comprising a cylinder, an inlet valve at the bottom thereof, a piston therein, an inlet valve in the piston, a shaft connected to the piston and extending above the cylinder to form a supporting shaft, a connecting head at the upper end of the shaft, a tiltable sealing cup mounted on the cylinder for creating a seal across the well casing, means urging the cup into sealing position, and means carried by the shaft for causing the cup to assume non-sealing position when the shaft is above its upper pumping stroke position.
